WET SUIT HANGER

Donald G. Papineau, 26 Willow Road,
Greenville, R.I. 02828

Filed Apr. 29, 1968, Ser. No. 11,653

Term of patent 14 years

Int. Cl. D6—07

U.S. Cl. D80—8

FIG. 1

FIG. 2

FIG. 3

FIG. 4

FIG. 1 is a front elevational view of a wet suit hanger showing my new design;

FIG. 2 is a side elevational view thereof;

FIG. 3 is a top plan view thereof; and

FIG. 4 is a bottom plan view thereof.

I claim:

The ornamental design for a wet suit hanger, substantially as shown.
